BATTERY CAP

James Linn Rodgers, 9606 La Serna, Whittier, Calif.

Filed Feb. 9, 1962, Ser. No. 68,742

Term of patent 14 years

(Cl. D26—6)

FIGURE 1 is a perspective view illustrating a battery cap embodying my new design;

FIGURE 2 is an elevational view illustrating one side of the battery cap;

FIGURE 3 is a top plan view thereof;

FIGURE 4 is an elevational view taken from a position ninety degrees from that of the showing of FIGURE 2; and

FIGURE 5 is a bottom plan view.

The remaining two sides of the battery cap are the mirror images of the showings of FIGURES 2 and 4, respectively.

I claim:

The ornamental design for a battery cap, substantially as shown and described.
